ABSTRACT OF THE DISCLOSURE

The method of exploration for petroleum deposits which comprises collecting samples of formation waters from wells and determining the concentration of at least one transition metal in said waters as a component indicative of the presence of petroleum deposits.

This invention relates to a method of geochemical prospecting for hidden hydrocarbon deposits by analyzing subsurface brines or other waters for the presence of dissolved transition metals, in particular metals of the first transition series such as iron, cobalt, manganese, etc.

The search for hydrocarbon deposits by geochemistry has heretofore been conducted by seeking actual evidence of leakage from the deposits themselves. One method of geochemical prospecting has been conducted by making systematic collection of soil samples over an area to be mapped and testing the soil samples for a variety of components believed indicative of the presence of hydrocarbon deposits. Inorganic substances considered indicative include carbonates, bicarbonates, sulfates, sulfides, halides, etc. Among the other components for which these samples have been tested are the lighter paraffinic hydrocarbons which are presumed to have migrated from deep subsurface hydrocarbon deposits. One of the difficulties encountered with this method of prospecting is that generally there is a wide variation of the sorptive and retentive capacities of the soil samples taken over a plurality of locations. This is due primarily to the differences in chemical and physical properties of the soil itself. A pattern of such concentration values may thus not give a true indication of the proximity of hydrocarbon deposits. In other known methods of geochemical prospecting, techniques have been used for detecting extremely small concentrations of crude hydrocarbons dispersed in drilling fluids. One of the problems which has been encountered in this type of prospecting for crude oil deposits is that positive indications are obtained when the drilling fluid is contaminated with refined petroleum products, such as pipe-thread grease or lubricating oils. The present invention is directed to overcoming the problems encountered in geochemical prospecting such as discussed above.

In general, the present invention is directed to a method of geochemical prospecting wherein information concerning the proximity of hydrocarbon deposits or source beds is derived by collecting aqueous subterranean samples from prospect areas and wildcat wells and determining the concentration of dissolved transition metals in the samples. The presence of these dissolved transition metals is an indication that these subterranean waters have been in contact with or are near a petrolierous deposit since the reaction between crude oil and its associated formation waters results in reduction of the oxidizing capability of the waters. In other words, the waters are no longer capable of oxidizing the transition metals, such as iron, nickel, cobalt, etc., and the transition metals are, therefore, reduced. This reduction leads to an increase in the concentration of the transition metals in the formation waters because the metals are soluble in the reduced state but are highly insoluble in the oxidized state. Thus, the proximity to petroleum deposits is indicated by an in-

2

crease in the concentration of transition metals in the formation waters.

By measuring the concentration of dissolved transition metals in fluid samples obtained for instance from wildcat wells, even though considered to be "dry" holes, it is possible to determine whether a particular formation is completely barren or whether nearby portions may be petrolierous. Such information obtained by detecting transition metals in the subsurface waters or brines from wildcat wells may guide further drilling activity in the area. Transition metals in varying concentrations have been found in tests on "dry" holes and increasing metal concentration is interpreted as indicating the direction toward petroleum deposits.

In practicing this invention any suitable method of analysis may be employed, for example, atomic absorption. The samples for analysis may comprise formation waters obtained by swabbing, drill-stem test fluids obtained from a drill-stem test, or samples of underground waters obtained by any convenient means.

Generally speaking, in accordance with this invention, formation water samples are analyzed for their water soluble transition metals content, after which the results of such analyses are plotted. The results, when plotted, either in plan or in profile, or both, will show a pattern of generally increasing concentration toward an oil or gas deposit. It is, of course, true that there will be variations in the concentrations of the transition metals in the formation waters from different localities due to the history of the waters, formation surrounding the waters, etc., even in the absence of petroleum deposits; however, larger variations will be found due to the presence of buried petroleum deposits and, as a rule, the small natural variations are negligible as compared to the larger variations resulting from the presence of buried petroleum deposits. In the present invention, it is a trend, i.e. increase in the amount of transition metals in the water, and not the amount per se, that is indicative of the presence of petroleum. Also, although in some areas it has been found upon analysis that certain transition metals may not yield distinctive patterns, usually this failure to give a pattern adjacent a producing area will be confined to one, or a few, metals and the characteristic pattern will be shown by analysis for any number of the other transition metals which may be determined. Thus, it would be unwise to condemn an area because analysis for one metal failed to give a characteristic pattern, and the patterns of other metals should be obtained so that it can be determined whether or not a significant pattern is obtained with a majority of the metals. Even if a significant pattern is obtained with only one metal, which would indeed be a rare case, further exploration of the area would be in order.

Table 1 lists the concentrations of some transition metals in various formation waters, e.g., formation brines, from oil producing areas. These data compared with sea water demonstrate that the concentrations in formation waters are often hundreds of times that of sea water.

TABLE 1

	Sample	P.p.m. Fe	P.p.m. Co	P.p.m. Mn
60	S-5209	.37	-----	.34
	S-3074	2.4	1.2	3.4
	S-4775	40.5	.41	1.5
	S-9023	.45	.30	1.1
	S-1755	1.0	1.7	1.2
65	S-4624	1.1	.46	12.6
	S-5234	4.1	1.4	.80
	S-7034	.84	1.2	1.7
	S-8707	.45	.70	.38
	S-7946	33.5	.30	3.7
	S-7941	3.0	1.3	1.1
	S-7940	.68	1.5	.96
70	S-4721	.34	.41	2.6
	S-5313	1.5	2.1	1.2
	S-3909	.11	.41	.18
	Sea Water	.02	.0001	.01

The transition metal concentrations illustrated above reveal the general nature of the results attainable by the practice of the present invention. It is to be understood that the present invention is not limited to the particular metals listed but encompasses those metals, e.g. transition metals, which are soluble in the reduced state but are insoluble in the oxidized state, especially the metals of the first transition series including in addition to iron, cobalt and manganese, nickel, vanadium, titanium, chromium, and scandium.

It is claimed:

1. The method of exploration for petroleum deposits which comprises systematically collecting formation water samples from a prospect area and determining the concentration in the original samples of at least two metals of the first transition series which are soluble in water in the reduced state and insoluble in the oxidized state as an indication of the proximity of petroleum deposits,

and correlating the concentrations obtained with sample locations in the prospect area whereby information indicative of the presence of such petroleum deposits is obtained.
